MECHANISM FOR CUTTING AND PINKING FABRIC

George M. Hoskwith, New York, N. Y.

Application July 20, 1938, Serial No. 220,169

4 Claims. (Cl. 30—273)

My invention relates to an improved mechanism for both pinking and cutting cloth along a cutting line which is located between the original edges of the cloth.

One of the objects of my invention is to form a series of abutting or overlapping pinking cuts in the body of one or more layers of cloth or other material, between the edges of said layer or layers, so as to separate the layer or layers into two portions which have pinked edges.

Another object is to provide mechanism mounted on a base which can be moved relative to a table or support on which the layer or layers are located. Another object is to provide improved means whereby the base of the mechanism is moved intermittently, and said base is held stationary between intermittent movements.

Other objects will be stated in the following description and drawings which illustrate a preferred embodiment of the invention.

Fig. 1 is a perspective view illustrating the mechanism whereby one or more layers of cloth are simultaneously cut and pinked.

Fig. 2 is a diagrammatic perspective view illustrating the essential operating parts of the mechanism, with the pinking and cutting knife in its bottom position.

Fig. 3 is a view similar to Fig. 2 showing the knife in its upper position.

Fig. 4 is a sectional view in median longitudinal plane, partially in elevation.

Fig. 5 is a side elevation showing the top shaft of the device.

Fig. 6 is a plan view of the underside of the base of the device.

Fig. 7 is a sectional view on the line 7—7 of Fig. 4.

Fig. 8 is a sectional view on the line 8—8 of Fig. 6.

Fig. 9 is a detail perspective view showing the pinking knife and the supplemental cutting knife, said supplemental knife operating to cut any threads which are not cut by the pinking knife.

Fig. 10 is a section on the line 10—10 of Fig. 4, showing the overlapping of adjacent pinking cuts in the layer or layers of fabric.

It has heretofore been proposed to provide mechanism for pinking the edge of one or more layers of fabric. This is shown in United States Patent #2,052,630 issued on September 1, 1936. However, according to this patent, it was necessary to cut the fabric prior to pinking.

By means of the improved mechanism, one or more layers of fabric are cut and pinked simultaneously and intermediate the edges of said

layers so as to produce two pinked edges, and to sever the fabric along the line of cut.

Fig. 4 shows a motor casing 1 in which a conventional electric motor is located. This motor has the usual armature shaft 2 on which the usual fan blades 3 are mounted. These fan blades 3 have the function of ventilating the motor in the usual manner, and the casing 1 is provided with one or more openings in the usual manner.

The armature shaft 2 is provided with anti-friction bearings 4 at the top and at the bottom of the casing. These anti-friction bearings are provided with the retaining plates 5, which act as seals to retain the lubricant.

The upper end of shaft 2 passes through and it is keyed to a worm 6 which drives the counter-shaft. As shown in Fig. 2 the worm 6 is rigidly held on the shaft 2 by means of a lock-nut 7 which is screwed on a threaded part of said armature shaft 2 and which abuts the upper end of said worm 6. The lower end of the worm 6 rests upon a shoulder of the armature shaft 2.

In order to check up the alignment, timing, and proper operation of the parts of the machine, the armature shaft 2 can be turned manually by means of a knurled head 8 which is rigidly connected to the top end of the armature shaft 2.

The worm 6 meshes with a driven worm gear 9, which is keyed to a counter-shaft 10. As shown in Fig. 5, the worm gear 9 abuts a shoulder of the counter-shaft 10. The worm gear 9 is provided with a gear hub 11, which is connected to the counter-shaft 10 by means of a pin 12. As shown in Fig. 5, the counter-shaft 10 is provided with an intermittent driving worm 13, whose hub is connected to the counter-shaft 10 by means of a pin 15. The thread of said worm 13 is inclined to the longitudinal axis of the shaft 10 only along the portion of each turn of the thread of said worm-gear 13. This portion of the turn may be one-third thereof or 120°. I do not wish to be limited to this specific example but this is the preferred construction.

The inclined portions 14a of the thread of the worm gear 13, are shown in Fig. 5. These inclined portions 14a are continuous with the portions of the thread of the worm gear 13 which are perpendicular to the axis of the counter-shaft 10.

The result is to produce an intermittent turning of the gear 13 which meshes with the intermittent worm 13, and to hold said worm gear 13 locked against turning during the major portion of each revolution of the intermittent worm 13. The gear 13 is located upon a vertical shaft 17.

which is rotatably held in suitable bearings and said vertical shaft 17 is releasably connected to an aligned shaft 18, by means of a clutch 19 which may be of any conventional type.

5 In Fig. 2 the clutch 19 is shown as engaged or operative. The clutch 19 can be disengaged so as to uncouple the shafts 17 and 18. The clutch 19 can be disengaged by manually turning the shaft 20, which is mounted in bearings 21 which are provided on the outside of the motor casing 1. An ordinary torsion spring 22 maintains the clutch 19 in operative position.

The shaft 17 is provided with a key 23, and the upper part of the clutch is slotted so as to 15 slidably engage said key 23.

The shaft 18 is keyed to spur-gear 24 which meshes with a companion spur-gear 25. The gear 25 is keyed to a shaft 26. The gears 24 and 20 25 can be equal or their pitch circles may have any desired ratio, for the purpose of lengthening or shortening the movement of the machine on the cutting table. As shown in Fig. 4 the shaft 26 passes through a suitable bore of the standard S.

25 Again referring to Figs. 2 and 7, the shaft 26 is keyed to a bevel gear 27 at its lower end and this bevel gear 27 meshes with a bevel gear 28 which is keyed to the shaft 29. The shaft 29 may be designated as the propelling shaft. It is 30 provided with one or more propelling wheels 30, which are keyed thereto. The wheel or wheels 30 contact with a suitable cutting table T so as to move the entire mechanism intermittently relative to said table. The wheels 30 may have 35 rubber tires which project slightly below every other part of the base 60 in order to give traction.

Referring to Figs. 2 and 4, the shaft 10 is provided with a crank-disc 31. The crank-disc 31 is 40 provided with a crank pin 32, on which the usual connecting rod 33 is pivotally mounted. The lower end of the connecting rod 33 is turnably connected to the stud of a cross-head 34, which is guided in suitable slide bearings 35. The 45 guides or slide bearings 35 are rigidly connected to the frame of the machine.

The cross-head 34 is provided with a clamp 36 for releasably engaging the pinking knife 37. The 50 contour of said pinking knife 37 is substantially the same as that of the pinking knife which is shown in said United States Patent #2,052,630.

However, in the present embodiment, the upper 55 end of the pinking knife is engaged between the two halves of a clamp 36, instead of being held in position by means of a screw.

The knife 37 can be made by suitably machining the lower portion of a rod having a square cross section so that the lower portion will have a V section and the upper end of said knife 37 has a square cross section and said upper end 60 can be engaged efficiently by the two halves of the clamp 36, which are held together by screws as shown.

The supplemental straight edge knife 38 is 65 suitably connected to the cross-head 34 so that the knives 37 and 38 are moved up and down in unison by said cross-head 34. The supplemental knife 38 may be integral with the pinking knife 37.

70 Referring to Fig. 9 the supplemental knife 38 moves slidably between guide members 39 which are provided in the standard S. These guide members 39 are secured to the standard S, by means of rivets 40. The guide members may be omitted and knife 38 can operate in standard S.

As shown in Fig. 9 the supplemental knife 38 is provided with a cutting edge 41 at its bottom and said cutting edge is preferably of generally concave shape and its heel is lower than the outer point thereof. Said cutting edge may have any 5 shape, including a straight shape.

The link 42 is held non-turnably relative to the crank-pin 32 by means of a screw which passes through crank-pin 32. The link 42 has a recessed portion which fits over the rectangular 10 end of crank-pin 32. The median longitudinal line of the link 42 will therefore always coincide with the same radius of the crank-disc 31. The connecting rod 43 is turnably connected to the free end of the link 42 by means of a screw 44. 15 The center of the shank of the screw 44 is spaced from the center of the disc 31. Therefore, the axis of the screw 44 will move through a circular path of a smaller radius than the axis of the crank-pin 32, when the crank-disc 31 is turned. 20 Therefore, the connecting rod 43 has a smaller throw than the connecting rod 33.

Pin 45, which is integral with member 46, is turnably located in connecting rod 43 and is held in turnable relation to connecting rod 43 by a 25 screw or other suitable member. Rod 47 passes slidably through the member 46 and through suitable bearings 49, which are provided in the frame of the machine.

A set screw having a knurled head 48 holds the 30 rod 47 in adjusted position relative to the member 46. The rod 47 is held against turning by providing said rod 47 with a suitable vertical keyway or groove which is slidably engaged by the end of an adjustable screw 50, having a turned 35 down point to fit said keyway in rod 47.

The rod 47 is provided with a slideable collar clamp 51, which can be clamped to or released from rod 47 by means of a butterfly head-screw 52. Springs 53 and 54 are mounted upon the 40 rod 47. The upper end of the spring 53 abuts the underside of the member 46 and the lower end of the spring 53 abuts the upper surface of the collar clamp 51. The ends of the spring 54 respectively abut the collar clamp 51 and the 45 bearing 49. When the set screw which has the knurled head 48 is tightened so as to clamp the rod 47, the collar clamp 51 is loosened by the operator. The bottom end of the rod 47 is connected to a presser-foot P. When the rod 47 is 50 rigidly connected to the vertical member 46 by means of screw 48 the presser-foot P is moved down rigidly in unison with the member 46 so as to exert unyielding pressure on certain kinds of material, therefore holding the material tightly 55 in position while it is being cut and in order to prevent the material from creeping.

When the screw which has the knurled head 48 is loosened and the clamp 51 is tightened, the downward movement of the member 46 compresses the upper spring 53 against the tightened clamp 51 downwardly which in turn compresses lower spring 54 against bearing 49, thus moving the rod 47 downwardly, under yielding spring pressure. This provides a lighter yielding spring 60 pressure on certain kinds of materials such as cotton, gingham or other hard and unyielding materials. The rigid connection between the member 46 and the rod 47 is utilized in the cutting of flannel and other similar soft materials. 65

The lower end of the rod 47 is connected rigidly to a member 56 of the presser-foot P. The pin 55 is turnably mounted in said member 56. Levers 57 are connected to the pin 55 so that the levers 57 are turnable relative to member 70 75

56. The presser-foot wheels 58 are turnably mounted on the levers 57 and are adjusted by means of screws 48 and 52 to rest intermittently on the material to be cut. The levers 57 are connected by a cross-rod 59 and the member 56 is provided with blade-springs 59a which abut said cross-member 59, so as to offer yielding resistance to the up and down movement of the levers 57 relative to the member 56. Pin 69 limits the movement of levers 57.

The base 60 is connected to the standard S by means of screws 60a. The underside of said base 60 is provided with idler wheels 61 which are connected turnably to the ends of flat blade springs 62 which are connected to the base 60 by means of screws 63. The base 60 is provided with a front extension flap 64, which is turnably connected to the base 60 by means of hinge pintles 65. These pintles 65 are held in position by means of screws 66. The base extension flap 64 is held in normal downward position illustrated in Figs. 4 and 8 so as to press its outer edge against the table T by means of a wire spring 67. The forward movement of base 60 will cause flap 64 to slide under the bottom layer of material and to raise the layer or layers to cutting position.

As shown in Fig. 7, the bottom end of the standard S is provided with a recess in order to accommodate the drive wheel 30 and the gears 28 and 27. A plate 68 is connected to the base 60, in order to provide a housing for the gears 27 and 28 to keep the lint from interfering with the normal operation of the gears and drive wheel. Plate 68 may also act as a retainer for grease in which the gears operate.

The base extension flap 64 is provided with a top flat or planar portion of substantially uniform width and with two side portions of substantially triangular shape converging at or near front edge of flap 64. Therefore, the layers of cloth are raised along the inclined planar central portion and the pinking and the resultant cutting take place behind the rear end of this top panel on a line which is in the same plane with the median longitudinal line of said top portion.

Referring to Fig. 8, the standard S is provided with a recess 70 and a die 71 is located in said recess. The pinking knife and the cutting knife cooperate with suitable openings in the die 71 and standard S. As shown in Fig. 6, the die 71 is provided with a triangular opening for cooperating with the pinking knife. The cross-section of said triangular opening increases downwardly for lint clearance. The die 71 is held in position by means of screws 72. The underside of the base is also provided with a space Sa to permit the escape of the lint as indicated by the arrows in Fig. 6.

In operating the device, one or more layers of material to be cut are placed upon a cutting table T. The motor is then started, thus causing the entire mechanism to move intermittently and to be locked between intermittent movements. Portions of the layers of material are raised on the upwardly sloping extension of the base until the portions of the layers of material which are to be cut are located above the die 71.

The pinking knife operates in advance of the supplemental cutting knife so as to form a series of angular or arcuate cuts C, as shown in Figs. 9 and 10. The individual pinking cuts are made by a blade whose edge is not a single straight line. In the embodiment disclosed, the combined cutting and pinking edge has a plurality of straight-

line portions which are inclined to each other. For the purposes of the claims, a pinking cut which does not consist solely of a single straight line may be defined as non-rectilinear. The distance between the tips of the cut may be defined as the length of the cut. The base portions of these cuts C slightly overlap each other at the points Ca. Hence the length of a pinking cut is at least equal to, and preferably greater than, the intermittent movement of the machine between successive pinking cuts, so that successive pinking cuts either abut each other or overlap, so as to cut through the layers and also pink the cut edges. This overlap of the pinking cuts C causes said cuts positively to sever the fabric and to simultaneously form the pinked edges which are shown in Fig. 1. Due to many conditions, it is possible that the overlapping of the pinking cuts C at the points Ca may not be sufficient and that a few fibres of the fabric may remain unsevered. The supplemental knife 38 has the function of cutting these unsevered threads.

The layers of cloth are held stationary on the table while the mechanism travels through the layers of cloth in order to pink them and thus cut them.

The presser-foot maintains the layers of cloth under suitable pressure, depending upon the type of material which is being utilized, while the pinking cuts are being made.

The presser-foot comes into action preferably before each pinking cut is made and it holds the layers of cloth down while the pinking cut and the supplemental cut are completed. The knives leave the fabric before the pressure of the presser-foot is released. The mechanism is fed forwardly in its intermittent movement while the presser-foot and the knives are absolutely free from the fabric.

The operator can hold the fabric down in advance of the mechanism or this can be done by any suitable means.

Suitable weights can be placed upon the layers of fabric in advance of the mechanism.

When it is desired to move the mechanism freely on its four idler rollers 61, the shaft 20 is manually actuated so as to unclutch the shafts 17 and 18, thus releasing the gear 24 from the motor drive.

As shown in Fig. 10 standard S is wedge-shaped in horizontal cross-section, so as to separate the cut plurality of layers of material and that pinked edges will clear the knife 38. The said knife 38 only cuts the fibres which are not severed by the pinking cuts. The motor casing 1 has a guard-sleeve 1k which encloses gear 16, shafts 17 and 18, clutch coupling 19 and gear 24. The motor-actuated means therefore move the pinking knife back-and-forth in a predetermined path above the base of the mechanism. Said motor-actuated means are located and adapted to clear the fabric during the intermittent movements of the base. The standard S is also shaped to permit the cut portions of the fabric to diverge on each side thereof. Referring to Figs. 6 and 8, the base has a front extension which is inclined downwardly relative to the base, along a predetermined line. The propelling means 30 are actuated so as to propel the base intermittently in a direction which is perpendicular to said predetermined line, which is parallel to the axes of the hinge pintles 65. This construction permits the pinking knife to operate along a

cutting line which is located between the original edges of the layer or layers of fabric.

While I have shown a complete and preferred embodiment of my invention, numerous changes and omissions can be made without departing from its spirit.

I claim:

- 10 1. A cutting and pinking mechanism adapted to cut and pink a plurality of layers of material by a succession of pinking cuts, comprising a base, a propelling wheel mounted on said base, drive mechanism mounted on said base to actuate said propelling wheel intermittently so as to move said base intermittently, a motor mounted above said base, an upright standard supporting said motor, drive means forming a connection between the motor and said drive mechanism, cutting means vertically reciprocable relative to said base and standard, said cutting means and standard and the part of said drive means which is located between the top and bottom of said standard lying substantially in a common plane in substantially the line of travel of said base, and means actuated by said motor for vertically reciprocating said cutting means.
- 15 2. The mechanism of claim 1 in which the means for intermittently driving said propelling wheel comprises a horizontally positioned shaft actuated by the motor, a worm member mounted on said shaft and a worm gear in mesh with said worm member, said worm member having a por-
- 20
- 25
- 30

tion of each turn thereof perpendicular to the axis of its shaft and having another portion of each said turn inclined to said axis.

3. The mechanism of claim 1 including a vertical shaft actuated by the worm gear, said vertical shaft driving said drive shaft, a clutch carried by said vertical shaft, means carried by the casing of the motor and adapted to disengage the clutch to thereby arrest movement of said propelling wheel.

4. A cutting and pinking mechanism adapted to cut and pink a plurality of layers of material by a succession of pinking cuts, comprising a base, a propelling wheel mounted on said base, drive mechanism mounted on said base to actuate said propelling wheel intermittently so as to move said base intermittently, a motor mounted above said base, an upright standard supporting said motor, a drive mechanism forming a connection between the motor and drive means, the part of said drive mechanism which is located between the top and bottom of said standard being housed by said standard, cutting means vertically reciprocable relative to said base and standard, said cutting means, said part of the drive mechanism and standard lying substantially in a common plane in substantially the line of travel of said mechanism, and means actuated by said motor for vertically reciprocating said cutting means.

GEORGE M. HOSKWITH. 30
